UNITED STATES PATENT OFFICE.

ALFRED H. SMITH, OF NEW YORK, N. Y.

COMPARTMENT FREIGHT CAR.

Application filed June 9, 1920. Serial No. 387,518.

To all whom it may concern:

Be it known that I, ALFRED H. SMITH, a citizen of the United States, residing at New York city, in the State of New York, have **5** invented certain new and useful Improvements in Compartment Freight Cars, of which the following is a description.

In the handling of freight and express matter railroads are subjected to very serious financial losses due to theft of freight and express matter. Various expedients have been adopted and used to prevent or minimize such losses due to theft, but thus far no satisfactory expedient has been produced.

Another source of loss to the railroads has been the placing of freight on platforms where it is necessarily exposed to the elements and also to theft.

20 The object of my invention is to provide a series of independent freight and express holding compartments which may be loaded at the factory of the consignor and loaded on a railroad car where it remains undisturbed until it reaches its point of destination, and if the point of destination does not have a suitable housing for freight the compartment can be set intact and locked on the platform and function in that position as a freight warehouse protecting the goods from the elements and theft. It is contemplated to place a plurality of these compartments on a single car with the door of one compartment adjacent to the wall of the next adjacent compartment whereby only the imperforate walls of the compartment are exposed when the compartments are in position on the car.

A further object of my invention is to **40** provide means whereby the respective compartments are suitably and securely anchored and locked to the car against accidental displacement. The compartments are placed upon and removed from the car by means of a crane.

A further object of my invention is to position the side walls of the car beyond vertical plane of the outer face of the side sills of the car and position the stakes inside **50** of the side walls whereby the cubic capacity of the car is increased without increasing the over all dimensions of a standard car.

A further object of my invention is to utilize the wall stakes as anchoring means **55** for the compartments; and with these and other objects in view my invention consists

of the parts and combination of parts as will be hereinafter more fully set forth.

In the drawings:

Figure 1 is a longitudinal section of a **60** railway car with one compartment in position, parts being in elevation.

Figure 2 is a top plan view of Figure 1 with the freight compartment being in section.

65 Figure 3 is a transverse section of Figure 1, parts being in elevation with part of the section taken on line 3, Figure 2 looking in the direction of the arrow.

Figure 4 is an enlarged detailed sectional view through one of the car wall stakes and a corner portion of the compartment, on the line 4—4 of Figure 1.

The reference numeral 1 designates a gondola or other suitable type of car with side walls, two of which are secured to the side sills 3 by means of the Z bar 4 with suitable rivets, said Z bar running the entire length of the car. The wall stakes 5 are riveted to the inner face of the walls of the car and extend downwardly below the floor plane of the car and are riveted at their ends to the side sills of the car. These stakes are provided with a corrugation having an upper wall 6 and side walls 7, the side walls being flared outwardly so as to give a wedging effect. The upper end of the corrugation is tapered as at 8 to facilitate the engagement of another wedge member therewith.

80 The freight holding compartment 9 is **90** preferably constructed of sheet metal and is provided with a door 10 mounted upon hinges 11 and provided with a suitable locking means 12. The walls of the compartment extend, as at B shown in Figure 3, below the floor C of the compartment, said extended portion being reinforced by means of a U shaped channel bar A, and U shaped bar rigidifying the portion B of the walls of the compartment so that said projection **95** may function successfully as a base or foot to support the compartment when it is loaded on any surface whereby the floor of the compartment is prevented from coming in contact with water which may accumulate **100** on the surface on which the compartment may be placed, thereby protecting the goods in the compartment.

105 At each corner of the compartment I position a plate on wedging member 13 which is secured at one end to a wall of the car by means of the rivets 14, the other end of the

plate being bent around the corner of the compartment as at 15 and secured to another wall of the compartment by means of rivets 16, said rivets 16 passing through the plate 5 13, a wall of the compartment 9 and an angle iron 17 with which each corner of the compartment is reinforced.

The plate 13 is provided, intermediate its vertical edges, with two upstanding corrugations 18 the inner walls of which corrugations are connected by a web 19 whereby a space is formed between the corrugations 18 within which the corrugation on the stake 5 is adapted to be received after the 15 compartment is lowered onto the car. The walls of the corrugations 18 are preferably given a curvature, as at 20, more clearly shown in Figure 1, whereby the wedging action between the two wedge members is effective, but at the same time the two members may be separated vertically without undue stress upon either member or element to which the members are connected.

As a compartment is being loaded on the 25 car, it is positioned so that in lowering it onto the car the corrugations on the stake and on the compartment are centered so that when the compartment is fully seated on the car these corrugated wedge members securely 30 anchor and lock the compartment in the car against accidental displacement. The compartments are locked so that the door of each compartment faces a wall of the next adjacent compartment whereby it cannot be 35 opened and whereby the exposed walls of the compartments are imperforate.

It will of course be understood that 40 changes may be made in the details of construction without departing from the scope of the claims.

What I claim is:

1. The combination of a car having side and end walls and stakes secured to the inner face of said side walls, of a plurality of 45 independent freight compartments adapted to be positioned on said car, and locking means on the compartment to interlock with said stakes as the compartments are placed in position in the car, whereby the compartments are securely anchored in the car.

2. The combination with a car having side and end walls of stakes secured to the inner

face of side walls and provided with an outstanding corrugation, of a plurality of independent freight compartments adapted 55 to be positioned in said car and corrugations on the compartments adapted to interlock with the side stakes of the car when the compartments are in position on the car.

3. The combination with a car having side 60 walls, and stakes secured to the inner face of said side walls and provided with an outstanding corrugation tapered at its upper end, of a plurality of independent freight compartments adapted to be positioned on 65 said car, and a series of locking members of said compartments adapted to engage the corrugation of each stake and lock the compartment in position on the car.

4. The combination with a car having side 70 walls and stakes secured to the inner face of the side walls and provided with a vertically extending corrugation, of a plurality of independent freight compartments adapted to be positioned on said car, plates secured to 75 the walls of each compartment and each provided with a pair of vertically extending corrugations adapted to receive between them, as the compartment is being lowered into position, the corrugation of each stake 80 whereby the compartment is anchored and locked in the car.

5. The combination with a car having side and end walls, the side walls being positioned outside of the vertical plane of side sills 85 of the car whereby the cubic capacity of the car is increased, of stakes secured to the inner face of the side walls, of a plurality of independent freight compartments adapted to be positioned in said car, and locking 90 means on the compartments to interlock with said stakes after the compartments are placed in position on the car whereby the compartments are securely anchored to the car.

6. In a transportation unit, a pair of shipping containers, one side wall of each of said containers being equipped with doors, said containers being secured in position in said unit with door equipped walls contiguous to 100 each other.

In testimony whereof I affix my signature.

ALFRED H. SMITH,

DISCLAIMER

1,564,285.—*Alfred H. Smith*, New York, N. Y. COMPARTMENT FREIGHT CAR. Patent dated December 8, 1925. Disclaimer filed March 9, 1936, by the assignee, *The Less Carload Lots Company; The L. C. L. Corporation*, exclusive licensee, consenting.

Hereby enters this disclaimer to claim 6 of said specification.
